(57) **CLAIM**

The ornamental design for a sleeve for a height adjustable arm rest unit, as shown and described.

DESCRIPTION

FIG. 1 is a perspective view of a sleeve for a height adjustable arm rest unit incorporating the design of the present invention.

FIG. 2 is a front view of the sleeve.

FIG. 3 is a side view of the sleeve, the opposite side being a mirror image thereof.

FIG. 4 is a top plan view of the sleeve.

FIG. 5 is a rear view of the sleeve; and, FIG. 6 is a bottom plan view of the sleeve.
